UNITED STATES PATENT OFFICE.

GEORGE M. NORTON, OF SAN FRANCISCO, CALIFORNIA.

AMALGAMATOR.

Specification of Letters Patent No. 30,085, dated September 18, 1860.

To all whom it may concern:

Be it known that I, GEORGE M. NORTON, of the city and county of San Francisco and State of California, have invented a new 5 and useful Machine, that I call an "Eccentric Amalgamating-Mill," for Reducing and Amalgamating Gold and Silver Ores; and I hereby declare the following to be a true description of the construction and operation 10 of the same, reference being had to the drawings, which form a part of this specification.

Drawing No. 1 is a vertical section through the mill. The outer portion, represented by letters L L, L L, is made of cast iron in one 15 piece, with the openings N, M, O, for discharging the material, the center of which rises higher than the outside rim of the pan and forms a journal or bearing for shaft E, and thereby allows the water and material 20 all to pass or discharge from the openings M, N, O, without the possibility of injury to the bearing of the shaft E, the top of the center L L being cupped to admit oil, which may work down and through said bearing, 25 which prevents any oil or grease from getting into the mill to injure the amalgamation. The pan L L may be fastened firmly to any foundation or frame which allows the shaft E to be extended below the mill, to admit 30 of a pulley or gear, as shown by F, D, or any desired arrangement for motive power, to turn said shaft E. The shaft E passes through the center of the forearm 35 piece V V, which is made of cast iron, and bolted or otherwise fastened firmly to the inside pan or revolving center I I, which is made of cast iron, as shown, with double rim, and sufficiently less in diameter than the outer pan L L to leave a sufficient space 40 for the material operated upon to pass through and discharge at either of the openings N, M, O, desired. To the bottom or face of this revolving pan I I are attached the various plates J J and K, for reducing 45 and amalgamating as shown in the drawings. Plates J J and K are attached by bolts or screws. The revolving center I I with the plate K attached for amalgamating, can be raised by means of the screw on the 50 shaft E, and held by means of the set screws or key to any desired height, to allow a large or small quantity of mercury to be placed in the bottom of pan L L, thereby allowing the mill to be used as an amalgamator alone, 55 and suited to all classes of materials or ores,

whether in an oxid or crude state, containing gold or silver, provided said material is reduced to a proper fineness for amalgamating.

When either of the plates J, J, Figs. 2 and 60 4 drawing 3, and plate Fig. 2, drawing No. 2, are used on the center pan I I, the forearm piece V, V, with the center pan I I attached, is made to revolve with the shaft E, by the use of a key, fitted to a key-seat in 65 V, V, and a slot in shaft E, which key is made sufficiently loose to allow the entire revolving center to settle or drop as the reducing and amalgamating plates J, J, and the false or loose bottoms P, P, become worn, 70 which always keeps the plates J and P as close together as the material used in the mill will allow, until the plates are worn out. This grinding surface, in an annular form, as shown in the plates J and P, together with 75 the weight of the revolving center, and the motion of forty revolutions per minute, together with the even manner in which the ores are supplied through the pipes H, H, H, H, and the perfect manner in which the 80 projecting points O, O, of plates J distribute the ores as they run into the mill, makes it the most thorough reducing machine and the manner of forcing the ores over and in contact with the mercury, makes it a perfect 85 amalgamator.

The funnel G, G, is a circular annular casting, to which are attached the four pipes H, H, H, H, of sufficient diameter to pass 90 all the ores or matter required for the mill. The pipes are placed equal distances apart, that they may go between the arms V, V, and extend low enough in the center of the mill to prevent the ores and water from getting into the center L, L, or bearing to shaft 95 E thereby preventing the bearing of shaft E from wearing out. The funnel G, G, rests on the fore arm piece V V, and pipes H H dropping between the arms V, V, forces the funnel to revolve with the center 100 L, L, thereby distributing the materials as fast as received in the mill, and perfectly even over the entire center, from whence it is removed by the center points O, O, of the revolving plate J, attached to the center 105 L, L, which revolves evenly with the funnel. This manner of feeding through the revolving funnel G, G, and pipes H H on to the plate P P and between the plates J and P, is then taken and forced from the center 110

around and over the surface of the plates, to where it finds egress in one of the openings N, M, O, as described.

P, Fig. 1, drawing No. 2, shows a face view of the loose bottom plate P P, drawing No. 1.

The circular and cross-grooves or flutes are made as deep as the thickness of the plate will admit, in order to hold a sufficient 10 quantity of mercury for amalgamating.

Plate J, Fig. 2, drawing 2, shows a face view of a reducing plate, which is fastened by bolts or screws to the revolving center pan I, I, to the point O, O, shown from the 15 inside rim of the revolving pan L L to the center L L. There being an alternate space between the points to allow the material or ore as it drops or passes through the pipes H, H, on to the bottom plate P P, and the 20 eccentric curve to the points of plate J, forces the material from the center into the openings Z, Z, Z, Z, and then between the plates J and P which are close together. The openings Z Z crossing each other in an 25 eccentric manner as they do, and the bottom plate P being stationary forces the material or ores to traverse around and over the surface of the plates P, P, and over the grooves filled with mercury a great number of times, 30 thereby reducing the material or ores to a perfect powder and amalgamating every particle of gold or silver contained in the ores.

Plate K, Fig. 3, drawing 2, shows an eccentric amalgamating plate, to be fastened to revolving center L L, the same as plate J. This plate has curved cones or projecting cleats, made in a conical form, in the outside one of which, the curve is directly 40 the reverse from the one running to the center, which prevents or holds the material or ore from passing too rapidly to the periphery of I I, which reverse motion produces a perfect whirlpool or concentration 45 of the mercury, and thereby preventing the same from passing or escaping from the openings N, M, O, by which means all the valuable metals heretofore lost in the process of amalgamation, are saved. A sufficient quantity of mercury should be placed 50 in pan L L to suit the requirements of the material or ores used or passing through, to allow the projections to penetrate the mercury at least one-thirty-second part of an 55 inch, thereby causing the matter to pass under and through the mercury a great number of times, which produces perfect amalgamation. The revolving center pan I I should be graduated according to the height 60 of mercury in bottom of pan L L. The eccentric curves of the cones, cleats, or projecting cones, having so much greater distance to travel and being constantly immersed in water, prevent the direct egress of the material 65 and holds it as heretofore described:

thereby amalgamating all the metals that are susceptible of amalgamation. This plate, together with plate J, Fig. 2, drawing 2, is drawn reverse; so as to make it necessary to turn over the plate or drawing 70 with face down, to show it properly when revolving to the right, as the mill always moves when in operation.

Figs. 1 and 3, drawing No. 3, are loose bottom plates which fit in pan L L, the same 75 as P P in drawing No. 1. They are made in quarter sections showing the openings entirely through the plate. The advantage of making these plates in this manner is to secure the greatest durability, and retain the 80 method of preventing the mercury from being pulverized and escaping. The openings Z, Z, Z, Z, are intended in the bottom plates to be filled with mercury even full when the reducing plates are used. 85

Plates J, J, Figs. 2 and 4, drawing No. 3, are the upper revolving plates, made in quarter sections and bolted on to the pan I I in the same manner as the others heretofore described, the openings being retained 90 when in their proper place the same as shown in the drawings. 90

Fig. 2, drawing No. 3, shows the reverse curve in the openings 2, 2, which checks the flow of water and material in the openings, 95 and forces the material passing through the mill to remain under and between the plates sufficiently long to perform most perfect reduction and amalgamation.

Fig. 1, drawing No. 4, is a perspective 100 view of the mill set up on the frame, taken from the model. The inside revolving center I, I, is shown down, ready for use, the funnel G, G, with pipes H, H, going down between the arms V V and resting in its 105 proper place for use.

Fig. 2, drawing No. 4, is a perspective 110 of the mill with the inside center run up by means of the clamps 1, 1, fastened to the fore arm piece and the arm nut 2, 2, with the thread cut in the center to fit shaft E. By means of these clamps and this nut, the 115 whole inside center may be run up to any desired height in order to clean out the mill, or to substitute new plates for those worn out.

When the mill is properly cleansed and charged with mercury and run down to its proper place, as shown in perspective, Fig. 1, drawing No. 4, it is then ready for use 120 with proper conductors connected with the openings M, N, O, for disposing of the material, and conductors to the funnel G, G, for supplying it.

The inside rim of I I represented by 125 dotted line I in Figs. 2 and 4, drawing 3, also in Figs. 2 and 3, drawing 2, shows the inside rim of the revolving center I I, from which line the points O, O, project to the center L L. The space between the inside 130

rim of I I and the center L L forms a perfect funnel for the reception of all the material fed into the mill. It is here held and confined until it is removed by the points 5 O, O, as hereinabove described.

What I claim as my invention, and desire to secure by Letters Patent, is—

1. The combination of the circular, annular, revolving funnel G, G, with attached 10 pipes H, H, H, H; with the annular, revolving pan I, I, and annular plates J, J, and K; to compel the material to traverse from the center to the circumference, and insure the certainty of its being operated on 15 before it can possibly be discharged at the openings N, M, O.

2. The annular revolving pan I, I, and the annular plates J, J, and K, constructed and operated as set forth.

20 3. The manner in which the grooves or openings and projections in the different plates are arranged according to curved lines, as shown in the different drawings,

and the manner in which the projecting points O, O, of the plates J, J, and K take 25 the feed and force it from the center, as it passes through the pipes H H into the mill, causing an eccentric motion in the material under operation, thereby causing it to come repeatedly under the operation of the mill 30 or machine.

4. The manner of adjusting the inside center I I with the arms V, V, so as to leave any desired space between the revolving center and bottom of the pan L L, as 35 well as giving it great facility for being removed and held out of the way while cleaning out the mill or machine.

Dated at Grass Valley, Nevada county, California, the second day of May A. D. 40 1860.

GEO. M. NORTON.
